UNITED STATES PATENT OFFICE.

JAY L. KRAUS, OF CHICAGO, ILLINOIS, ASSIGNOR TO ALBERT PICK & COMPANY, OF CHICAGO, ILLINOIS, A CORPORATION OF ILLINOIS.

DESIGN FOR A BREAD AND BUTTER PLATE.

52,278.

Specification for Design.

Patented Aug. 20, 1918.

Application filed May 22, 1918. Serial No. 236,061. Term of patent 14 years.

To all whom it may concern:

Be it known that I, JAY L. KRAUS, a citizen of the United States, residing at Chicago, in the county of Cook and State of Illinois, have invented a certain new, original, and ornamental Design for Bread and Butter Plates, of which the following is a specification, reference being had to the accompanying drawing, forming part thereof.

In the drawings: Figure 1 is a perspective

of a bread and butter plate showing my new design. Fig. 2 is a transverse section.

I claim:

The ornamental design for a bread and butter plate as shown.

JAY L. KRAUS.

Witnesses:

MILDRED STUMPF,

KATHARINE GERLACH.
